ELECTRIC SWITCH FOR CONTROLLING A
NUMBER OF MAGNETO CIRCUITS

Frank Raymond Faber Ramsay, London, England, assignor to D. Napier & Son Limited, London, England, a company of Great Britain

Application March 8, 1941, Serial No. 382,442
In Great Britain March 14, 1940

2 Claims. (Cl. 200—16)

This invention relates to electric switches more particularly for controlling a number of magnetos associated with an internal combustion engine.

In the case of large internal combustion engines for aircraft a number of magnetos may be provided, for example each cylinder will have two sparking plugs whilst separate magnetos may be provided for two different banks of cylinders making four magnetos in all. One object of the present invention is to provide a form of multiple switch by which all the magnetos can be switched off simultaneously but if desired certain combinations of magnetos can be switched off momentarily without the others for testing purposes. It is also desirable that the switch should be of small frontal area so as not to occupy a large space on the already crowded panel of the aircraft.

According to the present invention a switch for controlling a number of magnetos to switch them off all together or separately comprises two operating members, namely a selecting member or handle for preselecting the magnetos to be connected to earth, and a connecting member or handle for causing the connection to be effected, wherein the two members are so interlocked and spring-biassed that the connecting handle will only remain in the "off" position when released if the selecting handle is so placed that all the magnetos are thereby switched off.

Conveniently the selecting handle serves to rotate a barrel switch mounted behind and perpendicular to a front panel so as to present a small frontal area. The barrel of this switch may be arranged to be moved longitudinally by the connecting handle to bring contacts on the barrel into engagement with stationary contacts or fingers.

The connecting handle is preferably in the form of a dolly or lever resembling that of an ordinary tumbler switch so that pilots accustomed to an ordinary tumbler switch will be able to switch off the magnetos in the customary manner. The connecting handle may, for example, act through a toggle mechanism to move the barrel of the barrel switch longitudinally against the action of a spring, and may be interlocked with the selecting handle by means which prevent the toggle from reaching the dead centre position, so that when so interlocked it springs back to the "on" position when released.

It is desirable that a single operating handle should serve to switch off all the magnetos in the ordinary way but at the same time the mag-

netos should not be connected together until they are all switched off by being connected to earth.

The invention may be carried into effect in various ways but one particular construction is illustrated by way of example in the accompanying drawing, in which

Figure 1 is a front elevation, and
Figure 2 is a sectional side elevation.

The switch illustrated is intended for an H-section engine having a dual ignition system using a front and a rear sparking plug in each cylinder. Each half of the ignition system, i. e. the front plugs or the rear plugs, is supplied by a twin magneto or pair of magnetos, one of which supplies the top banks of cylinders whilst the other supplies the lower banks. Moreover for testing purposes it should be possible to switch off the magnetos supplying the front sparking plugs of all the cylinders or those supplying the back sparking plugs of all the cylinders or for one magneto to be switched off at a time. On the other hand, the switch should be arranged to prevent both magnetos of the top cylinders or both magnetos of the bottom cylinders from being switched off unless all four magnetos are switched off and should also prevent the switch being left in such a position that only one or two of the magnetos are switched off.

The switch illustrated comprises a casing A having a removable top cover A₁ and a front panel B. Mounted in the lower portion of the casing is a spindle C₁ carrying an insulating barrel C which is provided with conducting segments C₂. The barrel switch is adapted to rotate about its axis in the hexshaft shown and also move longitudinally thereon, and is connected to a selecting handle D on the front panel by which it can be rotated. The barrel C is provided with a circumferential groove C₃ engaged by the lower end of a lever E mounted on a fixed pivot E₁ and connected by a link E₂ to the arm F₁ of a bell-crank F which projects through the front panel B and constitutes the connecting handle. This handle resembles the dolly or lever of an ordinary tumbler switch and the arm F₁ and the link E₂ constitute a toggle by which the barrel C is moved longitudinally when the lever F is actuated.

The arm E₂ is provided with a spring G which tends to move the barrel towards the front panel so that the barrel will only remain in its "off" position, remote from the front panel, when the lever F is depressed so far that the toggle passes over its dead centre. The selecting handle D is provided with any suitable means for holding

it in a number of predetermined angular positions and carries a disc **D1** having a slot or notch **D2** with which a projecting arm **F2** on the operating lever can engage only when the selecting arm and disc **D1** occupy the position shown in Figure 1. Thus unless the selecting member is in that position, the arm **F2** will engage the edge of the disc **D1** when the lever **F** is depressed and so prevent the toggle from moving over its dead centre, though moving the cylinder to its second position. Hence directly the lever **F** is released, under the action of the spring **G** it will return to the raised position shown in Figure 2 and thus return the barrel **C** to its first or "off" position.

Mounted within the upper portion of the casing is an insulated member **H** from which extend a number of blade contacts **J** engaging the surface of the barrel **C**. The barrel carries a number of conducting segments **C2** which are flush with its surface and are all connected together to the spindle **C1** and thence by means of a flange **C4** on the spindle to a spring contact **K** connected to earth. The segments **C2** are so arranged on the barrel that when the barrel is in the position shown in Figure 1, each segment is longitudinally spaced from the adjacent blade contact **J**, these blades and contacts being staggered in relation to one another. When however the barrel **C** is moved longitudinally away from the front panel by depressing the lever **F**, the segments **C2** are brought into alignment with the blade contacts **J** and this occurs whether or not the connecting lever **F** is moved downwards to the full extent (which can only occur when the notch **D2** occupies the position shown in Figure 1) as the barrel moves longitudinally before the toggle **F1**, **E2** passes its dead centre.

The circumferential arrangement of the segments **C2** is such as to preselect the desired combination of contacts so as to select magnetos to be switched off. Thus, in the example illustrated, if the selecting handle **D** occupies the central position shown in Figure 1, all the circuits will be connected together and hence the magnetos will be connected to earth and switched off. By rotating the handle **D** in a clockwise direction only the magnetos of the front sparking plugs are switched off. Thus if the handle **D** is moved so that the index "FTB" lies immediately below the lever **F**, both top and bottom magnetos are switched off. If it is moved into the second position so that the index "FT" occupies the central position below the lever **F**, only the magneto of the front top cylinder is switched off, and in the third position when the index "FB" lies immediately below the lever

F, only the magneto of the bottom cylinders is switched off. Similarly moving the handle in an anticlockwise direction so as to bring the markings "RTB", "RT" or "RB" into the central position below the lever **F**, produces corresponding results on the magnetos of the rear sparking plugs.

In addition to the contacts **J** required for switching off the magnetos, one or more further contacts **J1** with corresponding segments **C5** may be provided for associated auxiliary devices. For example, a set of contacts may be connected in the circuit of the under carriage warning light and arranged to break this circuit only when all the magnetos are switched off. In the same way for other purposes segments may be provided which make or break the circuit only when the barrel occupies a certain angular or axial position. For example, a double width segment of short angular extent may be provided to close a circuit whenever the barrel is rotated to a predetermined angular position whether or not all the magnetos have been actually switched off.

It will be appreciated that the construction described has the advantages referred to above. The frontal area of the switch is quite small, the form of the connecting handle resembles that of an ordinary tumbler switch, the magnetos are not connected together until they are connected to earth, only the desired combinations of magnetos can be switched off, and no magneto can be left switched off unless they are all switched off.

What I claim as my invention and desire to secure by Letters Patent is:

1. An electric switch for controlling a number of contacts having means to switch them all off together or separately, comprising a movable barrel having contacts, an operating member for rotating the barrel including a disc provided with a notch and forming a preselecting member for the contacts to be connected for effecting contact, a connecting member including a manually operated lever having a stop, a toggle mechanism and a spring connected therewith whereby the lever will be returned to its initial position directly it is released unless the stop on said lever registers with the notch in said disc, thus giving the switch the property of being both self-releasing and self-locking in accordance with the position of the preselecting member.

2. A switch mechanism as set forth in claim 1, including a relatively narrow elongated casing with means at one end to permit securement to an instrument board or the like.
